DESIGN FOR A DRESS ENSEMBLE

Aaron Guzy, New York, N. Y.

Application March 10, 1937, Serial No. 68,096

Term of patent 3½ years

To all whom it may concern:

Be it known that I, Aaron Guzy, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

The rear view of the dress unit is conventional.

The jacket portion of my dress ensemble is characterized by a contrasting lapel and sailor collar unit, contrasting cuffs and contrasting bottom border, which border extends upward to the central front opening to a diminishing point, as shown, said jacket constituting the dominant feature of the design.

I claim.

The ornamental design for a dress ensemble, substantially as shown, and described.

AARON GUZY.
